UNITED STATES PATENT OFFICE.

WILLIAM SELLERS, OF PHILADELPHIA, PENNSYLVANIA.

PNEUMATIC FIRE-EXTINGUISHER.

SPECIFICATION forming part of Letters Patent No. 269,965, dated January 2, 1883.

Application filed April 3, 1882. (No model.)

To all whom it may concern:

Be it known that I, WILLIAM SELLERS, of the city and county of Philadelphia, and State of Pennsylvania, have invented a new and useful Improvement in Pneumatic Fire-Extin- 5 guishers, of which improvement the following is a specification.

My invention relates to that class of fire-extinguishers in which water is confined within a portable apparatus under pressure from air within the same apparatus, the elasticity of the air supplying the means for expelling the water with the required velocity.

To proportion the relative charges of air and water under pressure in such portable apparatus so that the air will expel all the water with the required velocity, such apparatus, as heretofore constructed, have been provided with interior automatic appliances, or with interior 15 appliances operated through the side of the water-chamber, which determined the relative volumes of air and water under pressure, and to accomplish this and at the same time provide for charging and discharging, two or more 20 openings into the water-chamber have been requisite as part of the apparatus. These openings required fittings which could be opened and closed as demanded for the charging and discharging operations; and as such fire-extin- 25 guishers, to be most serviceable, should be stored, charged, and ready for use, it is of the highest importance that these fittings, when closed, should be absolutely tight, so as to prevent the escape of any fluid, and the conse- 30 quent loss of pressure, whereby the apparatus might be rendered useless when its service would be most important. It is very desirable, therefore, that the number of openings into the water-chamber should be as few as 35 possible, so that the liability to such accident may be reduced to a minimum.

It is the object of my improvement to simplify the construction of fire-extinguishers by discarding all of the apparatus within the vessel heretofore required to determine the volumes of air and water under pressure, and substituting an apparatus outside the vessel which at all times indicates the conditions of the charge and subserves all the requirements of 40 charging and discharging, so that the number of openings into the vessel may be reduced to 45

a single one; and to these ends my invention consists in providing a portable pneumatic fire-extinguisher apparatus with a single opening and a pressure-gage, said opening being 55 both the inlet and outlet for the charge, and said gage being so combined therewith that it shall indicate the relative quantities of air and water in the vessel as well during the progress of the charging operation as after its completion. 60

In the accompanying drawings, which form part of this specification, Figure 1 represents an elevation of my portable fire-extinguisher apparatus, partly in section; Fig. 2, a side-elevation of the force pump wherewith the apparatus is charged with air and water; Fig. 3, a sectional elevation of the faucet through which the apparatus is charged and discharged, and showing the connection to the pressure-gage 70 therewith; and Fig. 4, a horizontal cross-section of this faucet.

In all the drawings similar letters refer to similar parts.

The portable vessel A is made of tough, strong 75 metal, preferably copper or brass, and capable of containing with safety air and water under a pressure of one hundred and fifty pounds per square inch. It is provided with lugs on the outside, a a a a, (shown in dotted lines.) 80 through which straps or bands may be passed, whereby it may be more conveniently carried from place to place. It is provided with a single opening, f, through which it is charged and discharged, as hereinafter explained. To 85 this opening f, I fit the faucet B, containing a three-way plug, e, which, when turned open, gives free access to the interior of the vessel through the opening f, and to discharge the water to the lowest point in the vessel, when 90 the vessel is perpendicular, I propose to extend a pipe, d, from the faucet to said point in the vessel. The upper end of the plug e is provided with a square section, upon which is fitted a handle for operating the same, and above the 95 handle I mount upon the plug e a pressure-gage, H, of the usual construction, which communicates with the three ways in the faucet and with the interior of the vessel through a small hole in the axis of the plug, as shown in 100 Fig. 3, so that when the faucet B is open the pressure-gage is actuated by the varying press-

ure of the fluid as it is charged or discharged through this faucet, and when this faucet is shut the gage indicates the conditions of the charge within the vessel. To the outer end of the faucet B, I attach one end of a short flexible pipe, C, and on the other end of this pipe I provide a union, c, by which a discharging-nozzle, b, is secured to this pipe.

The pump for charging the apparatus is shown in Fig. 2. It is double acting, and the arrangement of piston rod or plunger, valves, and discharging-chamber is the same as shown and described in my application for a patent for an improvement in pumps, filed February 27, 1882, series of 1880, No. 53,777; but any form of force-pump that will work against a pressure of one hundred and fifty pounds per square inch, and which has the requisite attachments for the flexible pipes hereinafter described, would answer my purpose. The discharging-chamber of this pump is shown at D, and it is provided with a nozzle, to which the flexible pipe C may be attached by means of the union c, for which purpose the discharging-nozzle b must be first removed. The foot-valve chamber is shown at E, and it is provided with a nozzle, to which the flexible inlet-pipe F may be firmly secured in the ordinary way. This inlet-pipe may receive its supply from any convenient source; but in the drawings it is represented as taking water from the bucket G. In many cases it may be more convenient to provide a union upon the outer end of this pipe, whereby it may be conveniently attached to a water-supply under pressure, and I propose to avail myself of this arrangement where the circumstances favor it—as, for example, when the water alone has been discharged from the vessel A.

To charge the apparatus I remove the discharging-nozzle b from the end of the pipe C and attach this end of the pipe to the discharging-chamber D, as shown by the full lines upon the drawings, and turn the plug in the faucet B open. Then if the pump-valves are not perfectly air-tight—and with metal valves this is often the case—insert the end of the flexible pipe F in the water in the bucket G and pump

one or two strokes, sufficient to flood the valves in the pump; then remove the pipe F from the water and continue pumping with the end of this pipe in the air until the pressure of air in the apparatus indicates fifteen pounds upon the pressure-gage; then reinser the end of the flexible pipe F in the water and continue pumping until the gage indicates one hundred and fifty pounds. The apparatus is then fully charged. Turn the plug in the faucet B shut, disconnect the pipe C from the chamber D, and replace the discharging-nozzle b. The apparatus is then ready for use. It is evident that the same pump is capable of charging any number of such apparatus, and as the pressure-gage, which indicates the relative proportions of air and water in the charge, is always in connection with the interior of the vessel A, whether the plug in the faucet B is open or shut, its indications are always a faithful exhibit of the pressure in the vessel, and consequently as to its condition for service. By this method of charging the apparatus described the charge of air is forced into the vessel under so low a pressure that an ordinary pump is capable of performing the work, and following this charge of air with the charge of water through the same pump will further compress the air to the tension requisite for expelling the water with the desired force, so that the process of charging and the apparatus charged are alike reduced to the simplest elements.

Having thus described the object and nature of my invention, what I claim as new, and desire to secure by Letters Patent, is—

The combination, in a portable pneumatic fire-extinguisher provided with a single opening, of a faucet through which the vessel is charged and discharged, a flexible pipe, and a pressure-gage, the combination being and operating substantially as described, and so that the gage indicates the relative quantities of air and water in the vessel as well during the charging operation as after its completion.
